Attest:

United States Patent Office.

JOHN J. RYMAL, OF ROCHESTER, MINNESOTA.

Letters Patent No. 79,147, dated June 28, 1868.

AUTOMATIC SWING.

The Schedule referred to in these Letters Patent and making part of the same.

TO ALL WHOM IT MAY CONCERN:

Be it known that I, JOHN J. RYMAL, of Rochester, in the county of Olmsted, and in the State of Minnesota, have invented certain new and useful Improvements in Swings for Children; and do hereby declare that the following is a full, clear, and exact description thereof, reference being had to the accompanying drawings, and to the letters of reference marked thereon.

In the annexed drawings, forming part of this specification—
Figure 1 is a front view, and

Figure 2 a side view of the machine.

The nature of my invention consists in a swing for children, with a noiseless vibrating motion, which can be placed on the floor, hung to the ceiling, or hung to brackets in the wall, as may be desired, and providing it with means to give it more or less vibration.

To enable others skilled in the art to make and use my invention, I will proceed to describe its construction and operation.

I construct a case, A, of metal or other suitable material, inside of which I place clock-work, which drives the cam-wheel B on the front of the case. On top of the case are projecting flanges C C, with holes for screws, by which means the swing may be fastened to the ceiling if desired.

The case is provided with adjustable legs D D, which can be taken off and dispensed with when fastened to the ceiling, or when hung up on brackets in the wall by means of the angle and curve E of the bottom of the case, which thereby form its bearings. When attached to the ceiling it should be wound up with cord and pulley.

F is a lever, pivoted on one side of the top of the case, and has a wrist-pin, a, working in a groove, i, on the cam-wheel B, or it may be worked by an elevation or bead on the cam-wheel, with a pin on each side of it.

G is a rock-shaft, having its bearings in the sides of the case A, and has a pin, b, attached to it, which pin runs through a hole in the movable arm d in the lower end of the slotted lever F, thus communicating the motion of the lever to the rock-shaft G.

The movable arm d can be moved up or down in the lever F, through a slot therein, and fastened at any point desired, by means of a thumb-screw, e, thereby giving more or less vibration to the cradle.

The cradle or basket H is attached to a rod, I, which is hung on to the shaft G by means of a long hook, J, and can be lifted off and on at pleasure.

Having thus fully described my invention, what I claim as new, and desire to secure by Letters Patent, is—

1. The projecting flanges C C on top of case A, whereby it can be attached to the ceiling, substantially as and for the purposes herein set forth.

2. The angle and curve E in the bottom of case A, forming bearings, to hang it on brackets attached to a wall, substantially as and for the purposes herein set forth.

3. The adjustable legs D, to set it up or take it down at will, substantially as, and for the purposes herein set forth.

4. The adjustable connecting-rod I, attached to shaft G by means of hook J, and which can be lifted and on at pleasure, substantially as and for the purposes herein set forth.

5. The movable arm d on the bottom on lever F, fastened by means of the thumb-screw e, substantially as and for the purposes herein set forth.

6. The combination of lever F, arranged on the side of case A and cam-wheel B, producing a noiseless vibrating motion, substantially as and for the purposes herein set forth.

In testimony that I claim the foregoing, I have hereunto set my hand, this 6th day of April, 1868.

JOHN J. RYMAL.
